Primary Examiner — Paula Greene(74) *Attorney, Agent, or Firm* — Altera Law Group, LLC(57) **CLAIM**

The ornamental design for a headset for communication, as shown and described.

DESCRIPTION

FIG. 1 is a perspective view of a headset for communication showing my new design;

FIG. 2 is a front view thereof.

FIG. 3 is a back view thereof.

FIG. 4 is a left view thereof.

FIG. 5 is a right view thereof.

FIG. 6 is a top view thereof; and,

FIG. 7 is a bottom view thereof.

The features shown in broken lines depict environmental subject matter only and form no part of the claimed design.
